TOILET PAPER HOLDER

John H. Wilson, North Platte, Nebr.

Application November 3, 1937, Serial No. 172,635

1 Claim. (Cl. 242—55.2)

This invention relates to toilet paper holders.

An object of the invention is the provision of a holder for toilet paper in which a sleeve provided with a face plate is adapted to receive a cylindrical roll of toilet paper with one end of the roll abutting the face plate, said sleeve adapted to be received by a cylindrical member projecting from the wall of a room, said member being provided with a pivoted latch having its free end projecting through an opening in said member and adapted to be received by an opening in the sleeve so that when the sleeve is slipped onto the member the sleeve will be locked to the cylindrical member and will be retained upon said member until the paper has been removed from the sleeve.

Another object of the invention is the provision of a toilet paper holder adapted to be slipped over a member projecting from the wall of a room with internal locking mechanism for connecting the holder to the projecting member so that the locking means is entirely enclosed by the roll of toilet paper and will remain locked until the paper has been sufficiently removed to permit the release of the automatic locking means.

A further object of the invention is the provision of a theft proof holder for toilet paper so that when a roll of paper is in position the locking means will be hidden and will be protected by the roll of paper until such time when the paper has been withdrawn in the usual manner to expose the locking means.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claim.

In the drawing:

Figure 1 is a vertical section of a toilet paper holder constructed in accordance with the principles of my invention,

Figure 2 is a vertical section taken along the line 2—2 of Figure 1,

Figure 3 is a vertical section showing the holder in an unlocked position,

Figure 4 is a bottom plan view of the support for the holder, and

Figure 5 is a bottom plan view of the paper holder per se in detached relation from the wall support shown in Fig. 4.

Referring more particularly to the drawing, 10

designates a plate which is secured in any approved manner to a wall 11 of a room.

A cylindrical member 12 is formed integrally with the plate 10 and projects laterally therefrom. The outer end of the member, as shown at 13, is open so that when necessary the interior of said member may be inspected as will be presently explained. The bottom portion of the member is provided with an elongated opening 14 adjacent the point where the said member is connected to the plate 10.

A latch member 15 is pivotally connected at 16 to the walls of the member 12 adjacent the outer end and this latch member extends inwardly towards the plate 10. A curved finger 17 projects downwardly from the free end of the latch member 15 and has its free edge slightly rounded, as shown at 18. This finger projects through the elongated opening 14 through the force of gravity and the latch member is of sufficient weight for the purpose.

A face plate 20 of any suitable design is provided with an axially disposed sleeve 21 which extends laterally from said face plate. The outer end of the sleeve is provided with an annular shoulder 22 and the inner edge of this shoulder is rounded or beveled, as shown at 23. The walls of the sleeve, as shown at 24, are thickened adjacent the point where the said sleeve is connected to the face plate. The bottom wall of the sleeve 21 has an opening 25 to receive the free end of the finger 17 of the latch member 15 when the opening 25 is aligned with said finger and with the elongated opening 14 in the member 12. A roll of toilet paper 30 which has the usual cylindrical paper core 31 is mounted on the sleeve 21 and has one end abutting the inner face of the face plate 20 while the opposite end is adjacent the plate 10.

The operation of my device is as follows: The roll of toilet paper 30 is slipped onto the sleeve 21 and the sleeve is then shoved over the cylindrical projecting member 12 so that the portions 22 and 24 of the sleeve will act as bearings on the said member. The face plate 20 is then revolved until the finger 17 which engages the inner surface of the sleeve 21 aligns with the opening 25 when the said finger will fall into said opening and lock the sleeve to the member 12.

It will be seen by this construction that the parts are securely locked together against unauthorized detachment because the toilet paper 30 protects the finger 17 from manipulation and the inner end of the toilet paper adjacent the plate 10 also prevents removal of the screws 32.

When the toilet paper 30 has been removed from the support 31 it is only necessary to force a tool through the member 31 at a point where the finger 17 is engaged within the perforation 25 for raising the finger from said perforation whereby the face plate 20 may be withdrawn as will be the sleeve 21. The rounded end 18 of the finger at this time will ride over the beveled or curved edge 23 of the shoulder 22 and be forced into the cylindrical member 12.

A tongue 40 is connected to or formed integral-
ly with a projection 41 formed at the lower end
of the face plate 20 and this tongue projects lat-
erally from the face plate and extends towards
the base plate 10 which has an opening 42 on a
projection 43 at the lower end of said base plate
to receive the free end of the tongue 40 as shown
in Fig. 1 when the parts are in operative posi-
tion. This will prevent an unauthorized person
from attempting to rotate the face plate 20 at
anytime to remove the roll of paper 30.

As the paper is withdrawn from the roll it will
be pulled over one edge of the arm or tongue 40
in frictional contact therewith and this is done
to retard the speed at which the paper is drawn
from the holder under normal conditions.

The member 12 is provided with a raised por-
tion 45 which fits into a recess 46 formed in the
top at the outer end of the sleeve 21. The mem-
ber 45 in connection with the recess 46 and in

cooperation with the tongue 40 and the opening
42 prevent rotation of the face plate 20 and sleeve
21 when the parts are locked in an operative
position. Therefore it will be seen that the
tongue 40 has a double function in that it pre-
vents twisting of the face plate 20 when some-
one attempts to force the keeper 15 out of its
slot 25 and also acts in connection with the por-
tion 45 and cooperating recess 46 to properly
align the free end of said keeper with the slot 25. 10

I claim:

A theft-proof paper holder comprising a plate
having an opening and adapted to be secured to a
wall of a room, a tubular member projecting from
the plate and provided with a slot, a latch piv-
oted within the member and having a free end
normally projecting through the slot, a sleeve
slidably received by the tubular member, housed
by a roll of paper and having an opening adapted
to be aligned with the slot to receive the end of 20
the latch, a disc rigid with the outer end of the
sleeve, an arm projecting from the disc and hav-
ing the free end received by the opening in the
plate and cooperating means on the sleeve and
tubular member in conjunction with the arm, for
preventing twisting of the disc to unseat the latch
and for aiding in aligning the opening in the
sleeve with the slot in the tubular member. 25
